United States Patent Office

Des. 191,585
Patented Oct. 17, 1961

191,585

CHEERING ORNAMENT

Robert Eugene Miller, 75 Cedar Ave., Poughkeepsie, N.Y.

Continuation of design applications Ser. No. 52,714 and
Ser. No. 52,715, Sept. 22, 1958. This application Nov.
21, 1960, Ser. No. 62,900

Term of patent 14 years

(Cl. D34—15)

FIG. 1

FIG. 2

FIG. 3

FIG. 4

FIG. 5

FIG. 6

FIG. 1 is a front view of a cheering ornament showing my new design, as employing a basketball motif;

FIG. 2 is a side elevational view thereof;

FIG. 3 is a rear elevational view thereof;

FIG. 4 is a front view of a cheering ornament showing my new design as employing a football motif;

FIG. 5 is a side elevational view thereof; and

FIG. 6 is a rear elevational view thereof.

This application is a continuation of prior co-pending applications Serial No. D. 52,714, filed September 22, 1958, now abandoned and No. D. 52,715, filed September 22, 1958 now abandoned.

I claim:

The ornamental design for a cheering ornament, as shown and described.
